UNITED STATES PATENT OFFICE.

GEORGE F. HAHN, OF NEW YORK, N. Y.

PEN AND PENCIL CLIP.

1,347,090.

Specification of Letters Patent. Patented July 20, 1920.

Application filed March 26, 1920. Serial No. 368,823.

To all whom it may concern:

Be it known that I, GEORGE F. HAHN, a citizen of the United States, residing at New York city, borough of Manhattan, 5 county and State of New York, have invented a certain new and useful Pen and Pencil Clip, of which the following is a specification.

This invention is a clip adapted to be associated with a pencil for the purpose of securing the same within the pocket of a garment so that it cannot become inadvertently detached and lost.

Practically all of the clips heretofore suggested for this purpose have been of a type which depended entirely upon friction between the clip and the garment, and, while such structures operate tolerably well for a while they become strained through prolonged use and fail to properly carry out their function with the result that the pencil or pen is not securely held within the pocket and not infrequently works loose and becomes lost.

25 The object of the present invention is to so construct a clip that it will tightly grip the garment and securely and positively hold the associated pen or pencil in the pocket as long as it is used.

30 The clip of the present invention does not depend upon friction to hold the pen or pencil in position, but takes a positive grip on the garment until such times as it is manually released to allow of removal and use 35 of the pen or pencil.

40 Features of the invention, other than those specified, will be apparent from the hereinafter detailed description and claims, when read in conjunction with the accompanying drawings.

The accompanying drawings illustrate different practical embodiments of the invention, but the constructions therein shown are to be understood as illustrative, only, 45 and not as defining the limits of the invention.

Figure 1 illustrates a clip embodying the present invention, said clip being shown in position on a pencil.

50 Fig. 2 is a central longitudinal section through the clip shown in Fig. 1.

Fig. 3 is a section on line 3—3 of Fig. 1.

Fig. 4 shows details of construction of the clip of Figs. 1 to 3; and,

55 Fig. 5 show a slightly modified form of construction.

Referring to the drawings, and more particularly to Figs. 1 to 4, inclusive, 1 designates a holder or frame, which may be conveniently stamped of sheet metal after the manner shown in Fig. 4, and thereafter suitably bent into the shape illustrated in Fig. 1. It will be noted from Fig. 4 that the stamped up blank embodies a pair of lateral wings 2, which, when bent down as shown in Fig. 1, form a pair of gripping members adapted to embrace a pen or pencil 3, for the purpose of supporting the holder on said pen or pencil. The shank 4 of the blank 1 is bent to form a supporting arm or bracket, the free end of which carries lateral projections 5 adapted to be bent down to form supporting lugs which are perforated to allow of the passage of a pin 6 therethrough. On the pin 6 and between the lugs 5 are mounted one or more star wheels 7 adapted to be spaced apart and from the lugs by spacers 8, as clearly shown in Figs. 3 and 4.

The blank 1 is further provided with a 80 resilient tongue 9, which is stamped up from the body of the blank as shown in Fig. 4, and when the blank is bent up as described, the tongue 9 will extend in a rearward direction, as clearly shown in Figs. 1 and 2, and will protrude for an appreciable distance from the rear portion of the arm 4.

Riveted or otherwise secured to the tongue 9 is a spring finger 10, shown in detail in Fig. 4, and this spring finger reaches 90 forwardly and normally projects through an aperture 11 in the forward end of the arm 4, and engages with the star wheels 7, as best shown in Fig. 2. It will be noted that the end of the spring finger 10 engages 95 with the star wheels in angular direction to the radii of said wheels, and this construction thus permits of the rotation of said wheels in one direction, but positively precludes their rotation in a contra-direction, 100 the action between the star wheels and spring finger thus simulating the action between a pawl and ratchet.

When the clip as thus far described is positioned on a pen or pencil, the thrusting of the pencil into the pocket may be so accomplished that the outer face of the pocket may be readily passed between the arm 4 and the pencil in the manner common to clips as previously employed, and during 110 the downward movement of the pencil, the star wheels 7 will be brought into engage-

ment with the outer face of the pocket and roll over the goods, said wheels during this operation riding idly beneath the coöperating end of the spring finger 10. This operation may be carried on without any manipulation of the clip whatsoever and is accomplished automatically through the positioning of the pencil in the pocket. However, any attempt of the pencil to work out of the pocket will be thwarted by the star wheels 7 which tightly grip the fabric of the garment and are precluded from such rotation as would allow of the removal of the pencil by the spring finger 10 which locks said wheels against turning in a retrograde direction. In order to remove the pencil from the pocket, it is necessary for the operator to flex the tongue 9 toward the pen or pencil as shown in dotted lines in Fig. 2, whereupon the free end of the spring finger 10 will be shifted free from engagement with the star wheels and allow said wheels to rotate during the unrestricted removal of the pencil.

It will thus be apparent that the clip of the present invention does not in the least interfere with the positioning of the pencil in the pocket but positively locks the pencil in position within the pocket until such times as it is manually unlocked through the flexing of the spring tongue 9. As soon as the tongue is released, the spring finger 10 is automatically returned to engagement with the star wheels and remains in this condition during subsequent use and replacement of the pencil in the pocket. It need not again be operated until it is desired to remove the pencil from the pocket for its subsequent use.

The construction shown in Figs. 1 to 4 and hereinbefore described, may be employed either in connection with pencils or pens of any character, and may be readily positioned thereon, by simply bringing the resilient wings 2 of the holder into a position to embrace the pen or pencil. However, in Fig. 5 I have illustrated a slightly modified form of the invention, which is particularly adapted for use with fountain pens. In this construction, the holder, instead of being provided with the spring wings 2 adapted to embrace the pen, is formed with projections 11 adapted to be inserted through slots in the cap of the pen and bent over for the purpose of securing the holder in place upon said cap. The construction of Fig. 5 is otherwise the same in all particulars as shown in the remaining figures of the drawing, this latter figure illustrating merely a different mode of attachment of the clip to the pen or pencil.

It will be understood that the specific invention described may be modified in formal respects, such as by the substitution of equivalents, and that parts of the complete

mechanism described may be used alone, or in other environments, without departing from the spirit or substance of the broad invention, the scope of which is commensurate with the appended claims.

70

Having thus fully described the invention, what I claim as new and desire to secure by Letters Patent is:

1. A pen or pencil clip embodying a holder adapted to be mounted on a pen or pencil and embodying an arm adapted to overlie the exterior of the pocket in which the pen or pencil is adapted to be positioned, a star wheel rotatably supported on said arm and adapted to engage with the exterior of said pocket, and means for locking the star wheel against rotation in a direction to permit of the removal of the pen or pencil from the pocket, whereby the pen or pencil is normally maintained in the pocket by the positive grip of the star wheel on the fabric of the garment.

2. A pen or pencil clip embodying a holder adapted to be mounted on a pen or pencil, a star wheel supported by said holder and adapted to engage with the exterior of the pocket, when the pen or pencil is positioned within the pocket and manually operable means for normally locking the star wheel against rotation, whereby the pen or pencil is normally maintained in the pocket by the positive grip of the star wheel on the fabric of the garment.

3. A pen or pencil clip embodying a holder adapted to be mounted on a pen or pencil and embodying an arm adapted to overlie the exterior of the pocket in which the pen or pencil is adapted to be positioned, a star wheel rotatably supported on said arm and adapted to engage with the exterior of the pocket, and resilient means associated with the holder and normally engaging with the star wheel for locking the star wheel against rotation in a direction to permit of the removal of the pen or pencil from the pocket, whereby the pen or pencil is normally maintained in the pocket by the positive grip of the star wheel on the fabric of the garment until such time as said star wheel is released by manual manipulation of the resilient means.

4. A pen or pencil clip embodying a holder adapted to be mounted on a pen or pencil embodying an arm adapted to overlie the exterior of the pocket in which the pen or pencil is adapted to be positioned, a star wheel rotatably mounted on said arm and adapted to engage with the exterior of the pocket, a resilient tongue carried by the holder and a stop member supported on the resilient tongue and normally engaging with the star wheel to lock the star wheel against rotation in a direction to permit of the removal of the pen or pencil from the pocket until such time as the resilient

120

tongue is manually flexed to disengage the stop member from the star wheel.

5. A pen or pencil clip embodying a holder adapted to be mounted on a pen or pencil and embodying an arm adapted to overlie the exterior of the pocket in which the pen or pencil is positioned, a star wheel rotatably supported on said arm for engagement with the exterior of said pocket, a resilient tongue integral with the holder and a spring finger mounted on the resilient
- tongue and engaging with the star wheel to normally lock the star wheel against rotation in a direction to permit of removal of the pen or pencil from the pocket, until 15 such time as the resilient tongue is manually flexed to disengage the spring finger from the star wheel.

In testimony whereof, I have signed my name to this specification.

GEO. F. HAHN.
